UNITED STATES PATENT OFFICE.

JOHN BOULTBEE BROOKS AND JOHN HOLT, OF BIRMINGHAM, ENGLAND.

CYCLE-SADDLE.

SPECIFICATION forming part of Letters Patent No. 698,367, dated April 22, 1902.

Application filed November 23, 1901. Serial No. 83,451. (No model.)

To all whom it may concern:

Be it known that we, JOHN BOULTBEE BROOKS, managing director, and JOHN HOLT, works manager, subjects of the King of Great Britain, residing at Criterion Works, Great Charles street, Birmingham, England, have invented certain new and useful Improvements in Cycle-Saddles, of which the following is a specification.

This invention relates to improvements in connection with the framings and pillar attachment-clips of cycle-saddles, and has for its object to provide such attachment-clips with a device or means which prevents the shearing of the frame wires or rods at the terminations of the parts where they are gripped by the clamping washers or plates of the said attachment-clips, thereby preventing breakages and enabling lighter and more springy framings to be employed than hitherto. To attain this object, each side of the clipping attachment is furnished or provided with an auxiliary spring-arm or spring-frame support which resiliently sustains the wires at points removed from the portions which are gripped by the washers or plates of the said attachment, the arrangement being such that the said brackets resiliently support or sustain the framing-wires against levering action caused by the weight of a rider upon the saddle.

According to one form of our improvements as applied to an attachment having rotating frame-gripping washers, each of the inner washers (which have keep grooves or seatings for the frame-wires to lie within, as usual,) is made from spring metal, preferably steel, and is provided with rearward extensions constituting a spring-wire-supporting bracket, which may either consist of separate arms independently supporting the respective wires or a frame having seatings, recesses, or rests in or upon which the wires lie and which is capable of a degree of flexible movement.

Figure 1 of the accompanying drawings represents a side elevation of part of a cycle-saddle provided with auxiliary means arranged in accordance with our invention for flexibly or yieldingly sustaining the frame-wires and preventing shearing or breakage of the same at points contiguous to the attachment-clip. Fig. 2 is an under side plan of a portion of Fig. 1 with a part in horizontal section upon

the dotted line x . Fig. 3 is a transverse vertical section of Fig. 1 upon the dotted line x' looking toward the attachment clip. Fig. 4 55 represents an elevation of one of the washers of the attachment-clip which carries the auxiliary means for supporting the wire rearward of the parts which are gripped by the said clip. Fig. 5 is an edge view of said washer. 60 Fig. 5^a is a longitudinal section of the same, taken in the line x^2 of Fig. 4. Fig. 6 is a side elevation of a slightly-different form. Fig. 7 is a transverse sectional view taken in the line x^3 of Fig. 6. Fig. 8 is a side elevation of 65 the frame-gripping washers carrying the resilient wire-sustaining bracket, and Fig. 9 is an edge view of the same.

Like characters refer to like parts in all the figures. 70

According to the form of our invention shown in Figs. 1 to 5, inclusive, each side of the attachment-clip a operates in connection with an extension or bracket b , adapted to resiliently support or sustain the framing-wires c , c' at points rearward of or removed from the parts which are gripped between the washers or plates d , e of the said attachment, the effect of providing such extended and yielding support being to neutralize any 80 tendency to excessive levering action of the back portions of the wire upon the terminations of their gripped and inflexible parts as fulcra, and also, consequently, prevent shearing or breakage of the wires adjacent to the 85 said parts. In the particular arrangement represented in Figs. 1 to 5 the resilient auxiliary extension-brackets b are carried by the rearward edges of the inner wire-gripping washers e , (which are made from spring steel,) 90 and the faces of the upright bars b' , connecting the two flexible bracket-arms b^2 , which are capable of yielding or moving with the wires more or less to the extent indicated by dotted lines in Fig. 1, are each provided with 95 a pair of grooves or horizontal seatings b^3 , corresponding to the keep-grooves e' in the washers e , and wherein the parts of the wires to which the additional support is to be afforded lie, and are thereby flexibly sustained 100 or upheld, but in such a manner as to not interfere with the resilient or spring action of the framing as a whole.

In the said Figs. 6, 7, 8, and 9, a is the at-

tachment-clip, and *c* the single-sided framing-wires, which are gripped and held between the clamping washers or plates *d e*. The resilient auxiliary support or flexible 5 spring device for preventing the shearing of the wires rearward of the gripped parts consists of an arm or extension *b*, directed from the rearward edge of the washer *e* and having a groove or open-fronted seating *b'*, forming an extension of the groove *e'* in the outer face of the said washer *e*, and wherein the framing-wire *c* lies and is resiliently supported or sustained at a point rearward of the parts which are gripped and rigidly held 10 between the washers *d e* in such a manner that excessive levering action and shearing of the wires is effectually prevented.

Instead of providing the attachment with resilient auxiliary wire-supports extending 20 rearwardly the same may extend forwardly, or both forwardly and rearwardly, and instead of the flexible antishearing brackets being carried by or formed as a part of one of the inner rotating washers of the clip they 25 may be carried by the outer washers or be

made in the form of separate attachments threaded upon the cross-pin or otherwise connected.

By the employment of resilient auxiliary supports such as above described lighter and 30 more resilient frame-wires may be used without risk of the same shearing adjacent to the parts where they are gripped.

Having fully described our invention, what we desire to claim and secure by Letters Patent is—

A pillar attachment-clip having washers grooved to receive the framing of the saddle, said washers having resilient extensions also grooved to receive said framing, and means 40 for holding the washers in place.

In testimony whereof we have hereunto set our hands in presence of two subscribing witnesses.

JOHN BOULTBEE BROOKS.
JOHN HOLT.
